Edgar E. Littlefield

UNITED STATES PATENT OFFICE.

EDGAR E. LITTLEFIELD, OF SEATTLE, WASHINGTON.

METHOD OF AND APPARATUS FOR AUTOMATIC ACTUATION OF MECHANISMS.

Original application filed February 5, 1913, Serial No. 746,417. Divided and this application filed September 11, 1919. Serial No. 323,142.

To all whom it may concern:

Be it known that I, EDGAR E. LITTLEFIELD, a citizen of the United States, and resident of the city of Seattle, county of King, State 5 of Washington, have invented certain new and useful Improvements in Methods of and Apparatus for Automatic Actuation of Mechanisms, of which the following is a specification.

10 This application is a division of an application filed by me on the 5th day of February, 1913, Serial Number 746,417, for methods of and apparatus for automatic actuation of mechanisms, which application 15 has eventuated into Patent Number 1335380, dated March 30, 1920.

My invention relates to methods of and apparatus for automatic actuation of mechanisms through the medium of temperature-20 responsive devices which are placed to be influenced by the varying temperature of a bath.

One of the objects of my invention is to provide a method and means for automatically regulating the flow of fluids and particularly for regulating the flow of fluid for flushing such apparatus as urinals, water closets, and the like. As is well known such fixtures as urinals which depend on proper 25 flushing by the use of timed devices or manual operation either waste considerable water or, as constantly happens, go unflushed. To overcome these objections I have developed and applied a method of operation 30 which is entirely automatic and practically instantaneous.

Other and further objects of my invention will become obvious, to persons skilled in the art, from a consideration of the following 40 description when taken in conjunction with the drawings wherein;

Figure 1 is a view, partly in elevation and partly in section, of a urinal employing a temperature-responsive device 45 in the form of a thermo-electric battery; Figure 2 is the same as Figure 1 except as to difference in location of parts.

Figure 3 shows a thermopile in conventional form together with the circuit arrangement and other parts more particularly described elsewhere in the specification.

I have found that the thermal conditions of the waste deposited in such recep-

tacles as urinals, water closets and the like, 55 is such as will operate a thermo-electric battery placed to be influenced thereby and the current developed applied to operate a relay, or analogous instrument, to thereby control or operate other forces or mechanisms.

Referring to Figure 1, 6 is a thermo-pile so placed as to be immersed in or otherwise directly affected by the fluid contents of the urinal or equivalent bath-containing vessel. These thermal couples are, of course, insulated from direct contact with the fluid, as indicated. Closely associated with and insulated from the thermal couples, are plates 60 which project into 65 the water and are also shown as extending across the discharge passage so that if a number were used, as would be the case, they will form a screen for solid matter deposited in the basin. These being in direct contact with the water are 70 kept cooled thereby. It is not deemed necessary to suggest a particular type of thermopile to be employed since one skilled in the art will be able to obtain in the open 75 market a type which will satisfactorily meet the requirements. The plates 60 are so arranged with respect to the pile as to assist in radiating heat from the junctions intended to be cooled. In Figure 1 they 80 are shown disposed near the bottom of the fluid-containing vessel where the temperature of the fluid is lower than at the surface, or near the same, where the junctions intended to be heated are placed. In 85 Figure 2 the plates are arranged outside the vessel where they are subject to the cooling effect of air currents. The function of the plates 60 being merely to assist in radiating heat from the cooled junctions intended to be heated are placed. In 90 Figure 2 the plates are arranged outside the vessel where they are subject to the cooling effect of air currents. The function of the plates 60 being merely to assist in radiating heat from the cooled junctions intended to be heated are placed. In 95

Freshly discharged urine has a temperature much higher than that of such water as would be used for flushing urinals. When discharged into the urinal it 100 will raise the temperature somewhat, which, acting upon the thermo-couples will produce a current of sufficient strength to actuate a relay, as 30.

Thermo-couples are very sensitive to 105 changes of temperature and will develop a sufficient current upon a very slight change of temperature.

In Figure 2 the construction is alike, except that the cooling plates 60 are without the bowl of the urinal and the plates which constitute the thermo-pile extend 5 through a hole in the bowl.

In this figure the heavier insulation has been omitted from that part of the thermopile outside the bowl for the reason that its use is unnecessary since the liquid is not 10 in contact with that part of the thermopile.

Upon use of the device, as of Figure 1, by deposit of waste a thermo-electric current will be generated in the thermo-pile 6 which current, flowing in circuit 61, will 15 actuate the relay 30, thereby controlling another and independent source of energy which may be applied through any suitable mechanism to perform any work desired. I have shown this relay as controlling a circuit 50, which contains an electrically operated valve 7, placed in the pipe 70, which supplies the flushing water for the urinal. The independent source of energy is represented by the battery 5, for which may be 20 substituted any other suitable source, as a dynamo. 51 and 1 are the armature of the relay 30, and the urinal bowl, respectively. This figure also shows a fan 72 operated by the water supplied to pipe 70 through the 25 water motor 71.

When the flushing action occurs the temperature of the bath is lowered and the generation of current reduced to such a point that the relay contact 51 will be opened. 35 throwing out of action the operating current in circuit 50.

It is evident that practically any other apparatus might be operated in an analogous manner.

40 There are many uses to which the principles of this invention may be put. It may be used to operate pumping or flushing apparatus; to care for sewerage, factory wastes and like purposes.

45 What I claim as my invention is:

1. A flushing system comprising, a receptacle to be flushed, a source of fluid therefor, a valve controlling the flow from said source to the receptacle, electro-magnetic 50 means controlling the operation of said valve, a circuit for said electro-magnetic means, and a temperature responsive device for controlling said circuit which is placed to be influenced by the temperature of the 55 fluid supplied by said valve.

2. The combination with a urinal, of

flushing means therefor including a temperature responsive device placed to be influenced by the temperature of the waste.

3. A flushing system comprising, a member to be flushed, a source of fluid therefor, a valve controlling the flow from said source to said member, a temperature-responsive device placed to be influenced by the temperature of the fluid received by said member, and operating means for said valve controlled by said temperature-responsive device.

4. A flushing device for waste receiving receptacles comprising, a thermo-electric 70 battery placed to be influenced by the temperature of the waste received by said receptacle, and means for applying the electricity generated by said battery to the operation of a flushing mechanism.

75 5. The combination with a urinal, of flushing means therefor including an electrically-controlled valve, a controlling circuit therefor and means for controlling said circuit comprising a temperature responsive 80 device which is placed to be influenced by the waste received by said urinal.

6. The method of controlling a thermally controlled electromagnetic flushing system which consists in automatically stopping the 85 flow of flushing fluid by exposing the thermal controlling means to the temperature of said fluid.

7. The method of controlling a thermally controlled electromagnetic flushing system 90 which consists in controlling the flow of flushing fluid by exposing the thermal controlling means to the temperature of said fluid.

8. The method of controlling a thermally 95 controlled electromagnetic flushing system which consists in subjecting the thermal controlling means to the temperature of the material to be removed and then subjecting it to the temperature of the flushing fluid.

100 9. The process of controlling the action of toilet flushing apparatus which consists in generating a thermo-electric current by the heat contained in the body wastes and using said current to energize the flushing mechanism.

In testimony whereof I have hereunto affixed my signature at Seattle, Washington, this 6th day of September, 1919.

EDGAR E. LITTLEFIELD.

Witness:

M. R. JAMESON.
